UNITED STATES PATENT OFFICE.

GEORGE H. CLARK, OF BROOKLYN, NEW YORK, ASSIGNOR TO RADIO CORPORATION OF AMERICA, A CORPORATION OF DELAWARE.

VARIABLE CONDENSER.

Application filed June 27, 1922. Serial No. 571,249.

This invention relates to electrical condensers and particularly to variable condensers utilized for example for changing the wave length of tuning circuits in radio 5 signalling.

A convenient variable condenser widely used in adjusting radio circuits utilizes spaced rotary, condenser plates mounted on a shaft in combination with similar stationary plates. The stationary and rotary plates are usually semi-circular, although they may, if desired, consist of two 90° sectors diametrically opposite. With semi-circular plates the variation from maximum to minimum 10 requires 180° rotation and with quadrants 90° rotation of the shaft. With this type of condenser it is found that zero capacity is not obtained when the plates are completely in non-opposition and the behavior more- 15 over is not reliable at or near this position, so that the useful capacity range is about 16 to 1. With a fixed inductance this corresponds to a wave length range of 4 to 1. This range is not as great as is desirable for many pur- 20 poses and the object of my invention is to provide a simple arrangement for obtaining a further increase in the range of capacity and wave length.

In accordance with the invention I pro- 25 vide two variable capacities, one large and the other small, in which the minimum capacity of the large capacity is preferably substantially equal to the maximum capacity of the smaller capacity. Both capacities 30 may be mounted so as to form a single con- denser and the variation of both capacities is controlled by a single adjusting member. In order to give a gradual variation the large condenser is short circuited at mini- 35 mum capacity and the small condenser is then varied down to its minimum.

The novel features which I believe to be characteristic of my invention are particu- 40 larly set forth in the appended claims, the invention itself, however, both as to its con- struction and mode of operation, together with further objects and advantages thereof, will best be understood by reference to the following description taken in connection 45 with the accompanying drawings in which:

Fig. 1 is a diagrammatic view illustrating a condenser arrangement in accordance with the invention.

Fig. 2 is a plan view of the short-circuit- 50 ing arrangement of Fig. 1.

Figs. 3 and 4 are diagrammatic views of modifications.

In these figures the invention is illustrated in connection with rotary condensers as it is especially applicable thereto. Semi-circular 60 plates are utilized although the invention is applicable to the rotary condensers using quadrants or plates of other shape.

In Fig. 1, two sets of plates 1, 2 are rotat- 65 ably mounted on the shaft 3, which is ad- justable in the usual manner by means of the adjusting knob 4 carrying a pointer 4' co- operating with a dial 4''. Two sets of plates 5, 6 cooperate with the rotary sets 1 and 2 respectively. The cooperating plates 1, 5 70 give the large capacity when opposite each other and the cooperating plates 2, 6 have a maximum capacity when opposite each other substantially equal to the minimum capacity of plates 1, 5. There are numerous arrange- 75 ments by means of which the combination of the large capacity and the small capacity may be secured and by means of which the gradual variation from the maximum of the large capacity to the minimum of the small 80 capacity may be produced. In the illustration of Fig. 1 the rotary plates 1 are ar- ranged on diametrically opposite sides of the shaft from the plates 2 which are smaller 85 in size and less in number, although both are preferably semi-circular in shape. The co- operating stationary plates 5 and 6 are on the same side of the shaft and the leading in wires are connected thereto. For short-cir- 90 cuiting one or the other of the condensers a brush 7 is attached to the shaft 3 and con- 95 tacts with either of the two semi-circular surfaces 8, 9, which are insulated from each other and connected respectively to the sta- tionary plates 5, 6. By rotating the adjust- 100 ing knob through 180° the capacity varies from the maximum of 16 of the large con- denser to its minimum of 1, bringing the plates 1 over to the right of shaft 3 and the plates 2 over to the left of the shaft. Dur- 105 ing this period the small condenser has been short-circuited because the stationary and ro- tary plates 2 and 6 thereof have both been connected to the ring 9. When the minimum of the large capacity is reached the brush 110 passes off of ring 9 on to ring 8, thus re- moving the short circuit on the small con- denser and placing it on the large condenser.

The plates 2 and 6 of the small capacity are directly over each other and in the position 110

of maximum capacity. During the next 180° of rotation of knob 4 this capacity decreases in the same ratio as that of the large condenser, that is, in the ratio of 16 to 1. In 5 this manner a range of capacity of 256 to 1 is obtained which corresponds to a wavelength range of 16 to 1 with a fixed inductance. This is secured by rotating the condenser knob through 360° , although, if desired, 10 the same range may be secured by 180° rotation of the knob by utilizing quadrants instead of semi-circular members.

Substantially the same result is secured by the modification of Fig. 3 which differs from 15 the form described in that the rotating plates 5 of the large condenser cooperate with the stationary plates 5 of the large capacity as well as the stationary plates 6 of the small capacity. The stationary plates are located 20 on opposite sides of the shaft instead of having the rotating plates on opposite sides.

The modification of Fig. 4 has the stationary plates 5, 6' on opposite sides of the shaft 3 as in Fig. 3 and separate rotatable plates 25 1, 2 for each capacity, the rotatable plates being located on the same side of the shaft. Two stationary brushes 11, 12 and a rotatable semi-circular ring 13 are used instead of one brush and two rings as in Figs. 1 30 and 3.

Having described my invention, what I claim is:

1. A variable condenser comprising two variable portions, one portion having a maximum capacity substantially equal to the minimum capacity of the other portion and means for short-circuiting the portions in sequence.

2. A variable condenser comprising two 40 variable portions, one portion having a maximum capacity when the other portion has a minimum capacity, a single adjusting means for both portions and means for short-circuiting each in sequence.

45 3. A variable condenser comprising a portion of relatively large maximum capacity and a second portion having a maximum capacity substantially equal to the minimum of the first mentioned portion, and means for 50 successively utilizing said portions including means for short-circuiting the portion not in use.

4. A variable condenser comprising a por-

tion of relatively large maximum capacity and a second portion having a maximum 55 capacity substantially equal to the minimum of the first mentioned portion, means for short-circuiting the large portion when at its minimum and the small portion at its maximum and adjusting means for varying both 60 portions and for operating said short-circuiting means.

5. A variable condenser comprising a set of rotary and a set of stationary sectors, one 65 of said sets being subdivided into two portions disposed at different positions relative to the cooperating sectors of the other set and means for applying a short-circuiting connection between the sectors of one of said portions and the sectors of the other set. 70

6. A variable condenser comprising a set of rotary and a set of stationary sectors, one 75 of said sets being subdivided into two portions disposed at different positions relative to the cooperating sectors of the other set and means for successively utilizing said portions.

7. A variable condenser comprising a set of rotary and a set of stationary sectors, one 80 of said sectors being divided into two portions disposed at different positions relative to the cooperating sectors of the other set and adapted to give two capacities such that the maximum of one is substantially equal to the minimum of the other and adjusting 85 members for varying the capacity of both portions having short circuiting members co-operating therewith for short-circuiting the last mentioned portion when adjusted to its minimum value and for short-circuiting the first mentioned portion when adjusted to its maximum value. 90

8. A variable condenser comprising a set of stationary sectors and a set of rotary sectors, said rotary sectors being divided into 95 two portions at different angular positions proportioned so that the maximum of one is substantially equal to the minimum of the other and positioned so that one reaches its maximum substantially simultaneous with the minimum of the other and means for short-circuiting the larger portion when its minimum is substantially reached and means for short-circuiting the smaller portion when its maximum is substantially reached. 100

GEORGE H. CLARK.
